SKETCH AND PAINT BOARD SET

Henry Hassenfeld, Providence, R. I.

Application May 22, 1939, Serial No. 274,881

10 Claims. (Cl. 41—4)

This invention relates to new and useful improvements in a sketch and paint board set.

The invention has for an object the construction of an article as mentioned which is characterized by a box for holding various sketching elements and a cover member for the box arranged in a certain manner so that it may be used for a sketch board as hereinafter more fully described.

10 Still further the invention contemplates characterizing the cover member by a front section which is attached to the front wall of the box, a bottom section hingedly connected with the front section and extending across the bottom of the box, a back section hinged to said bottom section and extending across the back of said box, a top section hinged to the back section and extending across said box, and a lip section hinged to the top section and extending down the front 20 of the box, and an arrangement whereby certain of said sections may be opened and used as a sketch board.

Still further the invention proposes the provision of various means for holding sketching paper upon said sketch board.

Another object resides in the provision of a paint palette comprising certain of said sketching implements and a novel arrangement for releasably holding said palette in certain positions 30 on said cover member.

For further comprehension of the invention, and of the objects and advantages thereof, reference will be had to the following description and accompanying drawings, and to the appended 35 claims in which the various novel features of the invention are more particularly set forth.

In the accompanying drawings forming a material part of this disclosure:

Fig. 1 is a perspective view of a sketch and paint board set constructed according to this invention.

Fig. 2 is a perspective view of the set shown in Fig. 1 with the cover member thereof opened so that the sketch board is ready for use.

45 Fig. 3 is a vertical sectional view taken on the line 3—3 of Fig. 1.

Fig. 4 is a fragmentary vertical sectional view taken on the line 4—4 of Fig. 2.

Fig. 5 is a transverse sectional view taken on the line 5—5 of Fig. 4.

Fig. 6 is a fragmentary perspective view similar to Fig. 2 but illustrating another embodiment of the invention.

55 Fig. 7 is a fragmentary sectional view taken on the line 7—7 of Fig. 6.

Fig. 8 is a fragmentary perspective view similar to a portion of Fig. 2 but illustrating another modified form.

Fig. 9 is a fragmentary sectional view taken on the line 9—9 of Fig. 8.

Fig. 10 is a plan view of a sketch board set constructed according to a further modification of this invention.

Fig. 11 is a fragmentary sectional view taken on the line 11—11 of Fig. 10.

Fig. 12 is a fragmentary sectional view taken on the line 12—12 of Fig. 10.

Fig. 13 is a fragmentary sectional view taken on the line 13—13 of Fig. 10.

Fig. 14 is a fragmentary horizontal sectional view taken on the line 14—14 of Fig. 13.

Fig. 15 is a fragmentary vertical sectional view taken on the line 15—15 of Fig. 13.

The sketch and paint board set, according to this invention, includes a box 10 having an open 20 top. A horizontal wall member 11 is mounted in the open top of said box and spaced slightly down from the top edge portion thereof. The box 10 includes side end walls 10^a and a bottom wall 10^b. The horizontal wall member 11 includes a top horizontal wall portion 11^a and vertical side and end wall portions 11^b. These side and end wall portions are arranged in intimate face contact with the inner faces of the side walls 10^a. The side edges of the wall portions 30 11^b rest upon the bottom wall 10^b.

The various sketching implements which are supported upon the horizontal wall 11 include a paint palette 12, a plurality of crayons 13, and a plurality of differently colored paint pieces 14. 35 The crayons 13 are mounted upon supporting brackets 15 which are fixedly mounted on the top wall 11^a. These supporting brackets 15 comprise a sheet of cardboard or similar material bent into a top wall 15^a, side walls 15^b, and bottom supporting flanges 15^c. These bottom flanges 15^c are pasted upon the top wall 11^a. The top wall 15^a is formed with a plurality of slots 16 through which the crayons 13 may be forced. The vertical walls 15^b are formed with circular 45 openings 17 through which the crayons 13 may extend. The arrangement is such that the crayons 13 are releasably held in position and may be forced from the brackets 15 when so desired.

The palette 12 has a plurality of paint pieces 50 18 mounted thereon at different positions. A cup for water 19 is also loosely mounted on the palette so that it may be removed and filled with water so that a painting brush may be suitably moistened and rubbed upon the paint pieces 18. The 55

paint pieces are pasted or cemented on the top wall 11^a.

A cover member 20 is provided for the box 10. This cover member has a front section 20^a which is attached upon the front wall 10^a of the box by several rivets 21. This front section 20^a hingedly connects with a bottom section 20^b which extends across the bottom wall 10^b of the box. A back section 20^c is hingedly connected with the bottom section 20^b and is adapted to extend up across the back wall 10^c of the box 10. A top section 20^d is hingedly connected with the bottom section 20^c and is adapted to extend across the open top of the box 10. A lip section 20^e is hingedly connected with the top section 20^d and is adapted to extend down the front wall 10^a of the box to a position in intimate contact with the front section 20^a. The various hinged connections between the sections of the cover member comprise creases or folds formed in the cover member transversely thereof so that the cover member may readily bend at these folded areas.

A means is provided for releasably securing the lip section 20^e together with the front section 20^a so that the cover may be unfolded and used as a sketch board. This means includes a latch having a keeper section 22 mounted upon the lip section 20^e and a bolt section 23 mounted upon the front section 20^a. These latch sections are capable of engaging each other for holding the cover closed, or these latch sections may be released so that the cover member may be opened. A handle 24 is mounted across the front section 20^a by which the sketch board set may be easily carried.

The operation of the device is as follows:

In Fig. 1 the sketch and paint board set is shown in its closed position. In this condition it may easily be carried about or stored when not in use. To use the set it is required that the latch 22, 23 be opened and the cover member unrolled from the box 10. The set is turned to a position so that the cover sections 20^c, 20^d and 20^e may rest on the table, while the cover section 20^b extends upwards at an inclination. A book or other article may be placed beneath the inclined section 20^b to hold the sketch board in this position. The cover sections 20^c, 20^d and 20^e may be used as a sketch board upon which sketching paper may be rested. The top face of the section 20^e is provided with the words "My sketch board" indicated by reference numeral 26. The box 10 may be pivoted upwards as indicated by the dot and dash lines 10' in Fig. 2 so that the top face of the section 20^b is exposed and sketching paper or other paper or sheet materials may be stored thereon.

In the modified form of the device illustrated in Figs. 6 and 7 flat sheet corner members 28 are mounted upon the top of the section 20^c for supporting a sketch sheet 29. In other respects this form of the invention is similar to the previous form.

65 In the form of the invention illustrated in Figs. 8 and 9 an elastic band 30 is mounted at its end portions 30^a upon the cover section 10^d. The intermediate portions of this elastic band 30 are free so that a sketch sheet 29 may be placed thereunder.

70 In the form of the invention illustrated in Figs. 10 to 15 inclusive clips 32 are mounted upon the cover section 20^d for releasably holding a sheet of drawing paper placed thereon. Moreover, in this form of the invention the palette 12' is re-

leasably mounted so that it may be removed and held in one's hand during sketching. The palette 12' is formed with an opening 12'' through which one may place his thumb when holding the palette. One end of the palette is held by clips 33 fixedly mounted on the top wall 11^a and extending over one edge of the palette. The opposite edge of the palette is provided with an eye member 36 which projects downwards through an opening 37 in the top wall 11^a.

75 A keeper 38 is slidably supported in a bracket 39 mounted within the wall member 11. A spring 40 normally urges the keeper 38 into an extended position. In its extended position it has a projecting end 38^a which projects from the rear wall 10^a. The arrangement is such that when the cover 20 is closed the section 20^c will engage against the projecting end 38^a of the keeper forcing it inwards as indicated by the dot and dash lines in Fig. 13 so that its inner end engages through the eye member 36 holding the same. This prevents the palette 12' from being loose when the drawing set is closed. When the cover 20^a is opened the palette 12' may be removed by first lifting up the end portion provided with the eye member 36 and then slipping the front end out from the stationary clips 35. In other respects this form of the invention is similar to the previous forms.

80 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to be secured by United States Letters Patent is:

85 1. A sketch and paint board set, comprising a box having an open top, a horizontal wall member mounted in the top of said box spaced slightly down from the top edge thereof for supporting sketching implements, a cover member for the box having a front section attached to the front wall of said box, a bottom section hingedly connected with the front section and extending across the bottom of said box, a back section hinged to said bottom section and extending across the back of said box, a top section hinged to said back section and extending across the top of said box, and a lip section hinged to said top section and extending down the front of said box, and means for releasably securing said lip section and front section together so that the cover may be unfolded and used as a sketch board.

90 2. A sketch and paint board set, comprising a box having an open top, a horizontal wall member mounted in the top of said box spaced slightly down from the top edge thereof for supporting sketching implements, a cover member for the box having a front section attached to the front wall of said box, a bottom section hingedly connected with the front section and extending across the bottom of said box, a back section hinged to said bottom section and extending across the back of said box, a top section hinged to said back section and extending across the top of said box, and a lip section hinged to said top section and extending down the front of said box, and means for releasably securing said lip section and front section together so that the cover may be unfolded and used as a sketch board.

board, said box having side walls and a bottom wall.

3. A sketch and paint board set, comprising a box having an open top, a horizontal wall member mounted in the top of said box spaced slightly down from the top edge thereof for supporting sketching implements, a cover member for the box having a front section attached to the front wall of said box, a bottom section hingedly connected with the front section and extending across the bottom of said box, a back section hinged to said bottom section and extending across the back of said box, a top section hinged to said back section and extending across the top of said box, and a lip section hinged to said top section and extending down the front of said box, and means for releasably securing said lip section and front section together so that the cover may be unfolded and used as a sketch board, said horizontal wall member including a top wall section and side wall section in intimate engagement with the side walls of said box.

4. A sketch and paint board set, comprising a box having an open top, a horizontal wall member mounted in the top of said box spaced slightly down from the top edge thereof for supporting sketching implements, a cover member for the box having a front section attached to the front wall of said box, a bottom section hingedly connected with the front section and extending across the bottom of said box, a back section hinged to said bottom section and extending across the back of said box, a top section hinged to said back section and extending across the top of said box, and a lip section hinged to said top section and extending down the front of said box, and means for releasably securing said lip section and front section together so that the cover may be unfolded and used as a sketch board, the attachment of the front section with said box being accomplished by rivets engaged through these parts.

5. A sketch and paint board set, comprising a box having an open top, a horizontal wall member mounted in the top of said box spaced slightly down from the top edge thereof for supporting sketching implements, a cover member for the box having a front section attached to the front wall of said box, a bottom section hingedly connected with the front section and extending across the bottom of said box, a back section hinged to said bottom section and extending across the back of said box, a top section hinged to said back section and extending across the top of said box, and a lip section hinged to said top section and extending down the front of said box, and means for releasably securing said lip section and front section together so that the cover may be unfolded and used as a sketch board, comprising a latch element having one section mounted on the front section of the cover member and the other section mounted on the lip section of the cover member.

6. A sketch and paint board set, comprising a box having an open top, a horizontal wall member mounted in the top of said box spaced slightly down from the top edge thereof for supporting sketching implements, a cover member for the box having a front section attached to the front wall of said box, a bottom section hingedly connected with the front section and extending across the bottom of said box, a back section hinged to said bottom section and extending across the back of said box, a top section

hinged to said back section and extending across the top of said box, and a lip section hinged to said top section and extending down the front of said box, means for releasably securing said lip section and front section together so that the cover may be unfolded and used as a sketch board, and means for securing sketching paper on said sketch board.

7. A sketch and paint board set, comprising a box having an open top, a horizontal wall member mounted in the top of said box spaced slightly down from the top edge thereof for supporting sketching implements, a cover member for the box having a front section attached to the front wall of said box, a bottom section hingedly connected with the front section and extending across the bottom of said box, a back section hinged to said bottom section and extending across the back of said box, a top section hinged to said back section and extending across the top of said box, and a lip section hinged to said top section and extending down the front of said box, means for releasably securing said lip section and front section together so that the cover may be unfolded and used as a sketch board, and means for securing sketching paper on said sketch board, comprising corner braces.

8. A sketch and paint board set, comprising a box having an open top, a horizontal wall member mounted in the top of said box spaced slightly down from the top edge thereof for supporting sketching implements, a cover member for the box having a front section attached to the front wall of said box, a bottom section hingedly connected with the front section and extending across the bottom of said box, a back section hinged to said bottom section and extending across the back of said box, a top section hinged to said back section and extending across the top of said box, and a lip section hinged to said top section and extending down the front of said box, means for releasably securing said lip section and front section together so that the cover may be unfolded and used as a sketch board, and means for securing sketching paper on said sketch board, comprising an elastic band.

9. A sketch and paint board set, comprising a box having an open top, a horizontal wall member mounted in the top of said box spaced slightly down from the top edge thereof for supporting sketching implements, a cover member for the box having a front section attached to the front wall of said box, a bottom section hingedly connected with the front section and extending across the bottom of said box, a back section hinged to said bottom section and extending across the back of said box, a top section hinged to said back section and extending across the top of said box, and a lip section hinged to said top section and extending down the front of said box, means for releasably securing said lip section and front section together so that the cover may be unfolded and used as a sketch board, and means for securing sketching paper on said sketch board, comprising 50

10. A sketch and paint board set, comprising a box having an open top, a horizontal wall member mounted in the top of said box spaced slightly down from the top edge thereof for supporting sketching implements, a cover member for the box having a front section attached to the front wall of said box, a bottom section hingedly connected with the front section and extending across the bottom of said box, a back section 70

hinged to said bottom section and extending across the back of said box, a top section hinged to said back section and extending across the top of said box, and a lip section hinged to said top section and extending down the front of said box, means for releasably securing said lip section and front section together so that the cover may be unfolded and used as a sketch board, said sketching implements including a palette, clips 5
10 engaging over the front edge of said palette, an eye member projecting from the rear edge of said palette and extending through an open-

ing in said top wall, a board slidably mounted upon a bracket supported within said horizontal wall member and having a projecting end projecting from the rear side wall of said box, resilient means urging said keeper into an extended position, and the rear section of said cover member being engageable against the bolt when the cover member is closed, to force in the bolt so that its inner end engages said eye member to hold said palette in position. 10 5

HENRY HASSENFELD.
